UNITED STATES PATENT OFFICE.

EDWARD C. SMITH, OF BROOKLYN, NEW YORK.

RAIL-SAWING MACHINE.

SPECIFICATION forming part of Letters Patent No. 340,682, dated April 27, 1886.

Application filed September 10, 1885. Serial No. 176,728. (No model.)

To all whom it may concern:

Be it known that I, EDWARD C. SMITH, a citizen of the United States, residing at Brooklyn, in the county of Kings and State of New York, have invented a new and useful Improvement in Rail-Sawing Machines, of which the following is a full, clear, and exact description.

My invention relates to improvements in machines for sawing off railway bars or rails; and the object of my improvement is to provide a machine of this character which is portable, simple, and inexpensive in construction and effective in operation with but little expenditure of power. This object I accomplish by the mechanism shown in the accompanying drawings, in which—

Figure 1 is a front elevation of a rail-sawing machine embodying my improvements. Fig. 2 is a side elevation of the same. Fig. 3 is a transverse section taken on the line $\alpha\alpha$ of Fig. 2, and Fig. 4 is a perspective view of the sliding carriage removed from the main supporting frame.

A represents the main frame, on which is mounted the operating mechanism. This is an elongated rectangular frame having open sides, and provided at the lower end with jaws B C, one of which, B, is curved inward, and so shaped as to form a bed or rest for the rail B', which is firmly clamped thereto by means of a threaded bolt, c, working through a correspondingly-threaded opening in the opposite jaw, C.

D is an inner frame or carriage fitted within the main frame A, and arranged to slide up and down between ways or guides $\alpha\alpha$, (see Fig. 3,) formed on the side bars of the frame A, which guides fit into corresponding recesses or depressions, $\alpha'\alpha'$, in the side pieces of the carriage D. To this sliding carriage is hung the carrying-frame for the saw.

On one end of a fixed shaft, f, projecting from the carriage D, is pivoted the frame E, so that it can have an oscillatory movement past the side of the frame A. The frame E is composed of two parallel bars closed at both ends, and provided at the swinging end with prolongations forming arms ee, between which is secured a serrated blade, N, the cutting-edge of which is the arc of a circle concentric with the pivotal point f of the frame E. The saw-

blade N is rigidly secured to one of the arms, and is held to the other and tightened by means of the screw-bolt n, which passes through an aperture in the arm e and receives the nut n' . 55

G is a horizontal shaft supported in bearings $g\ g$ in the side pieces of the sliding carriage D, with its ends projecting beyond the frame A, on one of which is mounted an eccentric, F, provided with a grooved rim adapted 60 to embrace the side bars of the saw-carrying frame E. On the opposite end of the shaft G is mounted the gear-wheel H, which engages a smaller toothed wheel, I, that is pivoted to a shaft projecting from the upper part of the 65 sliding carriage D, and which is turned by a crank, J.

A rotary movement is communicated to the eccentric F through gear-wheels H I, which causes an oscillation of the saw-carrying frame 70 E over the rail B'. As the saw-blade is carried back and forth, it is fed downward by the movement of the carriage D within the frame A, and the motion of the carriage is controlled by means of the vertical screw-shaft K, which 75 passes up through openings $d\ d$, formed in the cross-beams $d\ d$ of the carriage E, and is swiveled thereto by the set-washers L M. The upper and threaded portion passes through a threaded opening in the top cross-beam of the 80 frame A, preferably provided with a bushing, k, of soft metal, and terminates in a crank, k', by which it is rotated to lower the carriage D.

Instead of using a crank-motion for lowering the carriage D to feed the saw, I may employ means whereby the feed is automatic, being controlled by the same movement that operates the eccentric F. To effect this a cog-wheel, P, is mounted on the lower end of the vertical screw-shaft K, immediately over the 90 horizontal shaft G, which carries the eccentric F, and on this shaft are provided one or more projecting pins, Q, which, when the shaft G is rotated, will engage the cog-wheel and cause the rotation of the shaft K, lowering the carriage D. At the same time the rotation of the shaft G actuates the eccentric F and causes the oscillation of the frame E, carrying the saw-blade. 95

I claim—

1. In a rail-sawing machine, the combination of a vertical frame, a movable carriage

mounted therein, a saw-frame pivoted to said carriage, a horizontal shaft mounted in the carriage, provided with a grooved eccentric arranged within the saw-frame, and gear-wheels for actuating said shaft, as set forth.

2. In a rail-sawing machine, the combination of a main frame provided with ways, a carriage moving in said ways, a saw-carrying frame pivoted to a shaft projecting from the carriage, and a horizontal shaft mounted on said carriage and provided at one end with an eccentric confined between the side bars of the saw-frame, and at the other with a gear-wheel which engages a gear-wheel mounted on a shaft projecting from the upper part of said carriage, as set forth.

3. The combination of the main frame, the sliding carriage, the driving-shaft carrying an

eccentric, its operating mechanism, and a vertical screw-shaft swiveled to the sliding carriage and provided with a crank, as and for the purpose set forth.

4. In a machine for sawing off rails, the combination of a frame, a carriage mounted in said frame, with a pivoted saw-holding frame, a horizontal shaft carrying an eccentric, its operating mechanism, and a vertical screw-shaft journaled in the carriage and having a cog-wheel on its lower end adapted to engage with a stud on the main shaft, whereby the carriage is lowered to feed the saw, as set forth.

EDWARD C. SMITH.
